ELECTRONIC DEVICE, CIRCUIT, AND
METHOD

Thomas W. Cunniff, Newark, N. J., assignor to
Tung-Sol Lamp Works Inc., Newark, N. J., a
corporation of Delaware

Application March 11, 1941, Serial No. 382,693

12 Claims. (Cl. 178—5.8)

This invention relates to electronic devices, circuits and methods.

One object of the invention is a novel electronic generator or converter and circuit for producing pulsating electrical voltages or waves of a predetermined character, and a particular object is a generator for producing a saw-tooth voltage which by reason of its special character is particularly useful in the electronic art.

A further object of the invention is a novel and improved circuit for utilizing the electronic generator and circuit above referred to.

A further object of the invention is a novel method of producing a special voltage wave.

A further object of the invention is the utilization of an electron beam and resistance circuit for converting an alternating wave into a special wave shape.

A further object is the utilization of an electron beam as a commutator for producing a saw-tooth voltage.

The principle of the generator of this invention is of general application, but a particular object is to produce a pulsating voltage of the saw-tooth variety which is better adapted to the vertical or horizontal deflection of the electron beam in a television picture pick-up tube or a television picture reproducing tube than the pulsating voltages produced by prior devices and circuits. As applied to television the invention has among others the following advantages: The number of electronic tubes required in the conventional system may be substantially reduced, as for example, two tubes may be utilized to replace as many as six tubes of the conventional system; more of the time used in transmitting may be devoted to actual picture transmission; the entire synchronizing is or may be effected on the sound reception side of the circuit; the full magnitude of the wave is now available for the purpose of sending the picture signal; the picture is less subject to the effect of electrical interference; and the new system permits greater flexibility in the use of frame and line frequencies.

Other objects of the invention will hereinafter appear.

For a better understanding of the invention, reference may be had to the accompanying drawings forming a part of this application, wherein—

Fig. 1 is a perspective view diagrammatically illustrating the principle of the generator and circuit of this invention;

Fig. 2 is a modification thereof;

Fig. 3 is a diagrammatic view corresponding to Fig. 1, showing a preferred generator circuit;

Figs. 4 and 5 are plan and sectional views of a target which may be used with my invention;

Figs. 6 and 7 are perspective and sectional views of a modified form of target for use with the invention;

Fig. 8 is a view illustrating one of the wave forms produced by the generator of this invention;

Fig. 9 is a diagrammatic view of a television system embodying the invention; and

Fig. 10 shows a modified target.

Referring to Fig. 1 of the drawings, the generator, which may be termed an electronic wave converter, is illustrated as embodying an enclosure 1 which can be of glass for the purpose of permitting the tube to be evacuated or filled with gas. The generator or converter, aside from the circuits, embodies essentially three elements, namely an electron gun A, a beam deflecting means B and a target C. The electron gun A is for the purpose of producing and projecting the electron beam in the direction of the target C and may be of any conventional character with conventional circuits. The target C, in the particular embodiment illustrated, is a resistance in the shape of a slotted or interrupted annulus, the gap in the resistance being indicated at 16. This resistance element may have a varying resistivity or, as is preferred for television, should have a constant or uniform resistivity throughout. The beam deflecting means B in the embodiment shown comprises two pairs of deflecting plates 4 and 5 which are mounted at right angles to each other above the electron gun A or between the gun and the target C. This deflecting means is mounted so as to permit the deflection of the electron beam to any position on the target, and sinusoidal alternating current voltages differing in phase, preferably by 90°, are applied respectively to the pairs of plates 4 and 5, and these voltages are preferably of equal amplitude as well as displaced 90° so as to cause the beam to follow and traverse the annular resistance C. In the particular embodiment shown the multi-phase sinusoidal A. C. voltage is obtained from a single sinusoidal A. C. circuit 8, 9; this circuit being connected to one pair of the plates 4 and 5 while the other pair of plates 4 and 5 is connected with a conductor 15 leading to and connected at a point between a resistance 11 and a capacity 12 connected across the single phase line 8, 9.

A circuit D is connected with the terminals of the slotted or interrupted annular resistance element C and a circuit E is connected between one of the lines of the circuit D and the cathode 10

of the electron gun A. To one of these circuits D and E is applied a constant D. C. voltage and from the other is obtained the output voltage of the wave-shape desired, as for example, a saw-tooth wave-shape particularly suitable for television. In the preferred arrangement (Fig. 3) the constant direct current voltage is applied to the circuit E. When the direct current source is connected with the circuit D, a resistance is preferably connected across the circuit E.

Upon the application of a sinusoidal A. C. voltage across the terminals 3 and 9 and of a constant direct current voltage across the terminals E, the electron beam produced by the gun A is deflected onto the target and caused to traverse and follow the same at a uniform rate depending on the frequency of the A. C. supply voltage. This beam acts as a moving commutator, producing a saw-tooth output voltage across the terminals D. The frequency of the output voltage is equal to the frequency of the A. C. voltage across the terminals 3 and 9 while the magnitude of the output voltage depends on the resistance of the element C and on the beam current. As indicated, the output voltage wave-shape may be varied by providing a target C of a non-uniform resistivity. When the direct current voltage is applied to the circuit D, the output saw-tooth voltage, as above indicated, is produced on the circuit E, and in this case the magnitude of the output voltage depends on the voltage across the terminals 6 and 7, and the wave-shapes may be varied by providing a target of non-uniform resistivity or by applying other than D. C. voltage across the circuit or by altering the shape of the target.

In the embodiment of Fig. 2 the deflecting means B instead of being within the envelope 1 is disposed exteriorly of the tube and in this case this deflecting means preferably comprises two pairs of coils 4', 5', being shown in the drawing displaced 90° from each other, and the pairs of coils 4', 5' are supplied with alternating current differing in phase as for example by 90°, the supply circuit being omitted for convenience in illustration. In this case the electron beam is electromagnetically deflected while in the embodiment of Fig. 1 the beam is electrostatically deflected.

The target C is preferably formed of a thin annular layer or coating of resistance material which is slotted or interrupted at 16, and in the particular embodiment shown this is formed of carbon carried by a mica disc 17. This carbon resistance may be spraying on to the mica disc 17 while the carbon is in the colloidal form, and the commercial colloidal carbon sold under the trademark "Aquadag" has given satisfactory results. The ends or terminals of this resistance target C are connected with the terminals 20 and 21 leading to the circuit D, and this connection may be made in any suitable manner. It is understood that the resistance coating or target C is carried on the side of the mica or other insulating disc 17 exposed to the electron beam.

In the embodiment of Figs. 4 and 5 the target C extends all the way around the disc 17 except for the interruption or gap at 16, the disc itself being solid and uninterrupted. In the embodiment of Figs. 6 and 7 the disc 17 is itself slotted at 16, preferably along a radius, and the two adjacent edges at the slit are slightly displaced laterally of the plane of the disc so as to form a gap in the target resistance C, the ends of the latter extending to and through the slit 16 to the opposite side of the disc. In this case the terminals

20 and 21 are formed of sheet metal tabs which are fastened to the disc 17 in any suitable manner as for example by means of the screws or rivets 22, and the terminal 20 is formed with a projection 23 turned at right angles thereto into engagement with the disc at a point on the other side of the slit 16 for the purpose of maintaining a gap 18 between the ends of the annular resistance C. The carbon resistance C is extended around the edges of the walls of the slit 16 and extends under the terminals 20 and 21 to form the electrical connection. The terminals 24 lead to the circuit D.

As above indicated the electron gun A and the circuit for producing the electron beam may be of any conventional character. In the particular embodiment of Fig. 3 a direct current source 25 is connected to a resistance 26 and the latter has taps leading respectively to the conductor 15 and the first anode 27. The conductor 15 is also connected with the second anode 28. The control grid 29 is connected through a conductor 30 with one side of a battery 31 while the other side of this battery is connected with the line 32.

Fig. 8 illustrates the shape of the voltage wave obtained from the circuit D. The dotted wave indicates approximately the shape of the wave obtained by conventional devices and circuits, while the full-line wave indicates the wave obtainable according to the invention of this application. It is observed that there is considerable time wasted in the conventional wave in the drop from the maximum to the minimum, whereas in the wave produced according to the present invention the drop is substantially vertical, with the advantages indicated above. The points X, Y and Z of the wave correspond to the points X, Y and Z on the resistance element C successively traversed by the electron beam 3.

In the circuit D are illustrated condensers 35 of suitable capacity.

Fig. 9 illustrates diagrammatically a television system embodying the invention. First is a radio receiver which may be of conventional design for the purpose of receiving a radio signal, which consists both of the sound accompanying the television signal and the synchronizing signals, this being indicated at 36. In the output circuit of the radio receiver are two filters 37, one of which separates the vertical deflection synchronizing signal, while the other separates the horizontal deflection synchronizing signal. The sinusoidal output voltages from these filters are applied to the electronic wave converters 38 which convert the sinusoidal synchronizing signals into saw-tooth voltage waves, the latter being used for the purpose of horizontal and vertical deflection of the electron beam in the picture tube 40. Another radio receiver circuit 41 which receives the picture portion of the television signal is connected to the control grid 42 of the picture tube 40. It is understood that the picture tube 40 may be of any conventional type having any conventional deflecting means 43 and conventional electron gun 44.

This converter is of general application and has a number of important uses. As applied to television it has the following advantages: Two tubes replace six tubes of the conventional system. More of the time used in transmitting may be devoted to actual picture transmission. Previously a rather large part of the time was devoted to the transmission of synchronizing pulses. The time necessary for transmitting those pulses may be either reduced or eliminated, possibly,

with this method. With this improved converter system the entire synchronizing is effected on the sound reception side of the circuit and not only no time is wasted on the vision side but the full magnitude of the wave is now available for the purpose of sending the picture signal. Heretofore, a part of the magnitude of the wave, probably as much as 20%, was used in producing the synchronizing impulse, which reduced the efficiency of the picture transmission very substantially. The picture is less subject to the effect of electrical interference because of the nature of the signal transmitted. Since it is a sinusoidal synchronizing signal it is easier to filter it from extraneous signals or interference.

The system permits flexibility in the use of frame frequencies. The frame frequency and the line frequency are interdependent in that if one is high the other must be low and if one desires a high frame frequency it is necessary to reduce the number of lines per picture and, conversely, if one desires a large number of lines per picture one must reduce the number of frames per second. Deciding just what the value of frame and line frequencies must be is a matter of compromise in the conventional system and once established cannot be changed. By the use of electronic wave converters of this invention it is possible to devise a television system in which the frame frequencies and line frequencies may be varied in accordance with the demands of the subject-matter. This all may be accomplished without requiring any operations at the receiver.

The converter of this invention is also useful in electrical and radio research wherever a wave shape of the type is desired, and the shape of the wave may be varied as described above.

In Fig. 10 is shown a modification in which the target C is not provided with a gap 13. In this case the terminals of the circuit D are connected with the continuous ring target C at any two separated points, as indicated, for example, at 0 and 1, or at such points as will give the desired wave shape. The resistivity of the target C of any of the modifications may, instead of being uniform, be varied along its length to vary the wave shape, and the resistivity may be varied by varying the width of the annulus, varying the density of the target, etc.

I claim:

1. In an electronic wave converter, an envelope containing therein an electron gun and an annular resistance element disposed generally in a plane at right angles to the axis of the electron gun and adapted to receive the electron beam generated by the electron gun, means for deflecting said beam and causing it to traverse said annular resistance element, said annular resistance element being interrupted at one point to form a gap therein, a direct current voltage circuit and an output circuit, one of said circuits being connected to the terminals of said resistance element and the other of said circuits being connected between the electron gun and one of said terminals.

2. In an electronic wave converter, an envelope containing therein an electron gun and an annular resistance element disposed generally in a plane at right angles to the axis of the electron gun and adapted to receive the electron beam generated by the electron gun, means for deflecting said beam and causing it to traverse said annular resistance element, said annular resistance element being interrupted at one point to form a gap therein, a direct current supply circuit con-

nected between one of the terminals of said annular resistance element and the cathode of the electronic gun, and an output circuit connected to the terminals of said annular resistance element.

3. In an electronic wave converter, an envelope containing therein an electron gun and an annular resistance element disposed generally in a plane at right angles to the axis of the electron gun and adapted to receive the electron beam generated by the electron gun, means for deflecting said beam and causing it to traverse said annular resistance element, said annular resistance element being interrupted at one point to form a gap therein, a direct current voltage circuit and an output circuit, one of said circuits being connected to the terminals of said resistance element and the other of said circuits being connected between the electron gun and one of said terminals, and means for supplying to said deflecting means sinusoidal alternating current voltages differing in phase.

4. In an electronic wave converter, an envelope containing therein an electron gun and an annular resistance element disposed generally in a plane at right angles to the axis of the electron gun and adapted to receive the electron beam generated by the electron gun, means for deflecting said beam and causing it to traverse said annular resistance element, said annular resistance element being interrupted at one point to form a gap therein, a direct current voltage circuit and an output circuit, one of said circuits being connected to the terminals of said resistance element and the other of said circuits being connected between the electron gun and one of said terminals, means for supplying to said deflecting means sinusoidal alternating current voltages differing in phase, and circuits for said gun.

5. In an electronic wave converter, an envelope containing therein an electron gun and an annular resistance element disposed generally in a plane at right angles to the axis of the electron gun and adapted to receive the electron beam generated by the electron gun, means for deflecting said beam and causing it to traverse said annular resistance element, said annular resistance element being interrupted at one point to form a gap therein, a direct current voltage circuit and an output circuit, one of said circuits being connected to the terminals of said resistance element and the other of said circuits being connected between the electron gun and one of said terminals, the annular resistance element comprising an insulating disc support and an annular coating of resistance material carried thereby and exposed to the electron beam.

6. In an electronic wave converter, an envelope containing therein an electron gun and an annular resistance element disposed generally in a plane at right angles to the axis of the electron gun and adapted to receive the electron beam generated by the electron gun, means for deflecting said beam and causing it to traverse said annular resistance element, said annular resistance element being interrupted at one point to form a gap therein, a direct current voltage circuit and an output circuit, one of said circuits being connected to the terminals of said resistance element and the other of said circuits being connected between the electron gun and one of said terminals, the annular resistance element comprising an insulating disc support and an annular coating of resistance material carried thereby and exposed to the electron gun, said

insulating disc being slit at one point throughout the width of the annular coating with the edges of the slit being displaced laterally of the plane of the disc to form a gap in the resistance element while at the same time presenting a substantially continuous annular resistance target in directions normal to the plane of the disc.

7. In an electronic wave converter, an envelope containing therein an electron gun and an annular resistance element disposed generally in a plane at right angles to the axis of the electron gun and adapted to receive the electron beam generated by the electron gun, means for deflecting said beam and causing it to traverse said annular resistance element, said annular resistance element being interrupted at one point to form a gap therein, a direct current voltage circuit and an output circuit, one of said circuits being connected to the terminals of said resistance element and the other of said circuits being connected between the electron gun and one of said terminals, the deflecting means comprising two pairs of plates disposed between the electron gun and the annular resistance element, with said plates being energized in pairs from sinusoidal alternating current supply circuits differing in phase by 90°.

8. Means for producing a source of electric current having a predetermined wave shape comprising means for generating an electron beam, a resistance element of circular shape having a gap formed therein and disposed generally in a plane at right angles to the beam, means causing said beam to traverse said element at a predetermined rate as a commutating element, and an electrical circuit connected to said element at opposite sides of said gap.

9. In a television system, the combination including means for receiving radio signals and converting said signals into sinusoidal alternating waves, a picture tube having vertical and horizontal deflection means, and a pair of electronic wave converters each comprising the means set forth in claim 1, and each connected between said first mentioned means and one of

said deflection means for converting the sinusoidal waves into saw-tooth voltage waves for application to said deflection means.

10. In an electronic wave converter, an envelope containing therein an electronic gun and an annular resistance element disposed generally in a plane at right angles to the axis of the electron gun and adapted to receive the electron beam generated by the electron gun, means for deflecting said beam and causing it to traverse said annular resistance element, a direct current voltage circuit and an output circuit, one of said circuits being connected to said resistance element to cause a current to flow therethrough and the other of said circuits being connected between the electron gun and said resistance element.

11. In an electronic wave converter, an envelope containing therein an electronic gun and an annular resistance element disposed generally in a plane at right angles to the axis of the electron gun and adapted to receive the electron beam generated by the electron gun, means for deflecting said beam and causing it to traverse said annular resistance element, a direct current voltage circuit and an output circuit, one of said circuits being connected to said resistance element to cause a current to flow therethrough and the other of said circuits being connected between the electron gun and said resistance element, said annular resistance element is continuous with the circuits connected at different points thereof.

12. Means for producing a source of electric current having a wave approaching a saw-tooth wave shape comprising means for generating an electron beam, an annular resistance element which is interrupted at one point, and disposed generally in a plane at right angles to the beam means causing said beam to traverse said element and the interruption therein at a predetermined rate as a commutating element, and a circuit connected to said element at either side of the interruption.
